UNITED STATES PATENT OFFICE.

DUDLEY M. GODDARD, OF LINCOLN, NEBRASKA.

SCREEN-WIRE RACK.

1,278,906.

Specification of Letters Patent. Patented Sept. 17, 1918.

Application filed June 24, 1916. Serial No. 105,773.

To all whom it may concern:

Be it known that I, DUDLEY M. GODDARD, a citizen of the United States, residing at Lincoln, in the county of Lancaster and 5 State of Nebraska, have invented new and useful Improvements in Screen-Wire Racks, of which the following is a specification.

This invention relates to screen wire racks, the object in view being to produce a rack 10 adapted to contain any desired number of rolls of wire screen material, combined with guiding chutes through which the end portions of the wire screen stock are adapted to be fed one at a time, thereby enabling 15 the salesman to readily select the desired width of material and direct the same through its respective guiding chute to the cutting off point.

A further object of the invention is to 20 provide means for enforcing the feed of the material of any kind selected to the cutting off point; also means for registering the length of the material removed from any particular containing roller.

With the above and other objects in view, 25 the invention consists in the novel construction, combination and arrangement of parts, as herein described, illustrated and claimed.

In the accompanying drawings:—

30 Figure 1 is a front elevation of the rack of this invention.

Fig. 2 is a side elevation of the same.

Fig. 3 is a vertical fore and aft section through the device.

35 Fig. 4 is an enlarged fragmentary section illustrating the measuring mechanism.

Fig. 5 is a detail perspective view of the movable indicator.

In the preferred embodiment of this invention I employ a substantially triangular frame comprising a substantially rectangular base frame 1, main upwardly converging members 2 and 3 and another upwardly extending inclined member 4 substantially 40 parallel to the frame member 3. It is to be understood that the frame members 2, 3 and 4 are duplicated at opposite sides of the rack.

The members 3 and if desired also the 50 members 2 are provided with bearings 4' for the rollers or shafts 5 of any desired number of rolls 6 of screen wire. This is done in order to enable stock material of different widths to be mounted upon and dispensed from the same rack.

The members 4 of the frame are designed

for the support of the receiving ends of a plurality of guiding chutes 7 each comprising a top wall 8, a bottom wall 9 and sides 10. All of these chutes are open both at 60 their receiving and discharging ends and the end portions of the stock are inserted through said chutes and adapted to slide therein toward the point where the desired length of stock is severed from that remaining in the rack.

The chutes 7 converge toward a common discharge point and arranged adjacent to the latter are two feed rollers 11 and 12 which are journaled in bearing members 13 70 fastened in any suitable way to the frame members 2. The stock material is adapted to pass between said feed rollers 11 and 12 and to be drawn from the rollers and fed outwardly thereby, one of said feed rollers 75 being provided with an operating crank 14 on one end thereof.

Mounted on one of said feed rollers is a sprocket wheel 15 from which a chain 16 extends around another sprocket wheel 17 80 on a feed screw 18 which is also journaled in bearings on the frame member 2. The feed screw 18 is substantially horizontal and parallel to the feed rollers 11 and 12, being located above the latter. Located above the 85 feed screw 18 is a graduated scale bar 19 along which travels a pointer or indicator 20. The indicator 20 has a substantially semi-circular or forked base 21 which is internally threaded to be engaged by the 90 threads of the feed screw 18 when resting thereon. The point of the indicator 20 rests against the graduated bar 19. The indicator 20 by reason of its construction may be quickly and easily lifted off the feed 95 screw 18 and moved back to the zero point of the graduated bar 19 preparatory to dispensing another portion of the stock.

The rack may be placed on a counter, table or like support, stock of varying widths 100 may be carried by the same rack, each roll kept separate from the others, and by placing suitable symbols on the chutes 7 or on the frame adjacent thereto, the salesman may select the desired stock without handling a great number of rolls as is now necessary. In dispensing the stock, the end portion of the screen material selected is moved downwardly through its respective chute until the extreme edge thereof is engaged between the feed rollers 11 and 12. 110 The indicator 20 then being set at zero the

operator revolves the crank 14 until the indicator reaches the point indicating the length of material desired by the purchaser. The material is then severed closely adjacent to the feed rollers 11 and 12 by means of shearing blades 22 and 23 or by means of snips or portable shears as may be found expedient. It is preferred, however, to mount the shearing cutters upon the machine itself so that they will be immediately available.

While the drawings show the chutes as each having a top wall, in some cases the top walls of the chutes may be omitted as the bottom wall of one chute will practically form the top wall of the next lower chute.

Copies of this patent may be obtained for five cents each, by addressing the "Commissioner of Patents, Washington, D. C."

I claim:

A rack of the class specified comprising two connected triangular side frames arranged in spaced relation to each other, stock containing rollers journaled on said frame, a plurality of stock guiding chutes open at their receiving and discharging ends and converging from their receiving toward their discharge ends, inclined intermediate frame bars to which the receiving ends of said chutes are fastened, and a single set of manually operable feed rollers arranged adjacent to the convergent ends of said guiding chutes and journaled in bearings fastened to said frame.

In testimony whereof I affix my signature.

DUDLEY M. GODDARD.
